CHARLES F. STODDARD, OF NEW YORK, N. Y., ASSIGNOR TO AMERICAN PIANO COMPANY, OF NEW YORK, N. Y., A CORPORATION OF NEW JERSEY.

AUTOMATIC MUSICAL INSTRUMENT.

1,409,492.

Specification of Letters Patent. Patented Mar. 14, 1922.

Application filed January 25, 1917. Serial No. 144,392.

To all whom it may concern:

Be it known that I, CHARLES F. STODDARD, a citizen of the United States of America, and a resident of the city of New York, in the county and State of New York, have invented an Improvement in Automatic Musical Instruments, of which the following is a specification.

This invention relates to automatic means for playing musical instruments such, for instance, as pianos; and pertains more particularly to means for governing and varying tone intensities.

Among other objects, the invention is intended to provide apparatus capable of producing a great variety of variations in intensity of playing, such apparatus comprising preferably, though not essentially, a combination of means for producing crescendo and diminuendo effects and also instituting various defined grades or steps of playing intensity. For these purposes the invention may be embodied in apparatus which is very simple and reliable in operation.

For illustration, the accompanying drawings show one practical embodiment of the invention employing suitable pneumatically governed devices in cooperation with a piano action; but, as will appear to those skilled in the art, the invention is susceptible of embodiment in various constructions and organizations other than that particularly shown and described herein. It will appear likewise that it is not indispensable that all the features of the invention be used conjointly, since their respective substantial advantages may accrue from their separate application in any practicable manner to a suitable playing instrument.

In the drawings:

Figure 1 is a diagrammatic representation of a typical player action, with operating and governing means exemplifying the application and utility of the invention;

Figure 2 is a diagrammatic representation of a perforated note sheet such as may be used in cooperation with the apparatus of Figure 1.

Referring to the drawings, a striker or player pneumatic F is provided, having a sticker H to act upon a wippen I and thereby operate the usual piano action, as well

understood in the art. A wind trunk 7 leads to the wind chest for the motor pneumatics, each of which has a secondary valve 8 controlled by a primary valve 9 operated from a tracker-board G through a duct 10, in the usual manner.

The trunk 7 communicates with a regulated exhaust chest 12, which may be of any practicable construction. A high exhaust chest 14, arranged for communication with the chest 12, may be connected by a trunk 15 with any source of pneumatic exhaust, such as a diagrammatically shown feeder bellows 16, which may be of any practicable type.

For the purpose of explaining the general character of this invention, and to exemplify one practicable manner of governing tone intensities, I have selected the apparatus of the drawings in which the striking pneumatics F are caused to operate by the regulated exhaust in the chest 12, this regulated exhaust being varied, in order to vary the operation of the striker pneumatics, by subjecting it more or less to the influence of the high exhaust in the chest 14. For these specific purposes I have provided, between the high exhaust chest 14 and the regulated exhaust chest 12, a port 30, controlled by a throttle valve 31.

This valve 31 may be operated by a variety of different means. In this specific apparatus, the stem 32 of the valve 31 is connected to a movable board 33 of a bellows apparatus presently described, said board being hinged at 17.

Apparatus embodying this invention has a threefold capacity for controlling the valve 31. It produces automatically incremental changes in playing intensities; it performs a regulating function, i. e. it maintains any given playing intensity whether one or many notes be sounded; and it produces automatically continuously progressive changes in playing intensities for crescendos and diminuendos.

These three capacities of the apparatus will be described in the sequence indicated.

Beneath the board 33 are three bellows 34, 35 and 36, having their upper boards secured to the common movable board 33 and their lower boards secured to a fixed plate 18 as shown. The bellows may be made adjustable toward and from the hinge

17, to vary their leverages, in any practicable manner as by having their upper and lower boards, secured by screw and slot connections 19 and 20 to the movable board 33 and lower supporting plate respectively.

Another bellows 37 has its lower board secured to the movable board 33 and its upper board to a stationary plate 38. A condition of partial exhaust is maintained at 10 all times in the bellows 37 as presently described. The degree of exhaust in the bellows 37 may be varied; but for the present this capacity may be neglected and the pressure within the bellows acting upon the 15 board 33 may be considered uniform.

Thus, the pressure in the bellows 37 being always less than atmospheric pressure, said bellows in effect exerts continuously an upward pull upon the board 33, contributing 20 to control the valve 31.

Ducts 40, 41 and 42 enter respectively the bellows 34, 35 and 36. Each duct is controlled (as hereinafter explained) so as to admit to its bellows either atmospheric 25 pressure, or regulated pressure from the chest 12; and the regulated pressure may be admitted to any one or more or all of the bellows, while atmospheric pressure will be present in those bellows, if any, which 30 do not contain regulated pressure. Whenever regulated pressure (which is always less than atmospheric pressure) is present in one or more of the bellows 34, 35 and 36, the effect thereof is to produce a downward 35 pull upon the board 33 (i. e. the differential between atmospheric pressure on the top of the board 33 and the lesser regulated pressure in one or more of the bellows); and this resultant downward pull opposes 40 the upward pull by the bellows 37, the two contributing to control valve 31. High exhaust in the chest 14 exerts some downward pressure upon the area of the valve 31 itself; and the regulated pressure in the chest 45 12 exerts some upward pressure upon the area of the valve. The regulated pressure being greater, it predominates and the resultant upon the valve itself is an upward pressure which combines with the 50 resultant of the pressure in the several bellows to complete the control of the valve 31.

Thus the valve 31 is controlled by the differential between the upwardly acting pull of the bellows 37 and the pressure in the 55 chest 12 on the valve itself; and the downwardly acting pulls of such of the bellows 34, 35 and 36, as contain regulated pressure plus the downward pressure of highly exhausted air in the chest 14 on the top of 60 the valve 31. The areas of the various bellows, and their leverages in respect to the board 33, are such that these opposed upwardly and downwardly acting pressures so control the valve 31 as to tend to hold it 65 in a balanced condition. For example, if

regulated pressure be present in all three of the bellows 34, 35 and 36, the downward pull of these bellows upon the board 33 is at its maximum and tends to close the valve 31 and minimize the opening between the 70 chests 12 and 14. Such closing of the valve 31 and restriction of communication between the chests, tends to reduce the suction in the regulated pressure chest 12, and this reduction in suction is immediately 75 communicated to the bellows 34, 35 and 36, to reduce the downward pull thereby. In this manner the tendency to close the valve 31 is checked and it is closed to such an extent only as will produce a balance between the aforesaid downwardly acting 80 forces and the upwardly acting forces.

If, under these circumstances, atmosphere be admitted, for instance, to the bellows 36, the aggregate downward pull upon the 85 board 33, is relaxed to some extent tending to permit the upwardly acting forces to open the valve 31 correspondingly. If the valve be thus opened, the communication between the chests 12 and 14 is thereby 90 enlarged so that the degree of exhaust of the regulated pressure is increased and thereby the downward pull by the bellows 34 and 35 is correspondingly increased until the downwardly and upwardly acting forces 95 are again brought to a balance.

If atmosphere be admitted to all the bellows 34, 35 and 36 the downward pull by said bellows upon the board 33 will be minimized and the upwardly acting forces 100 referred to will so largely predominate that the valve 31 will be open to enlarge communication between the chests 12 and 14 to the maximum.

It will be evident to those skilled in the 105 art, that the more of the bellows 34, 35 and 36 which contain regulated pressure, the greater will be the aggregate downward pull by said bellows and the greater will be the tendency to constrict communication between the chests 12 and 14 by the valve 31. In other words, the more of the bellows 34, 35 and 36 which contain regulated pressure, the less is regulated pressure subjected to the influence of high exhaust and the less will be the intensity of sounded tones. Accordingly, the general operation of the bellows described may be conveniently summarized thus:—admitting regulated pressure to one or more bellows diminishes intensity; admitting atmospheric pressure to one or more bellows increases intensity.

In the operation of the specific illustrative apparatus the board 33 and valve 31 are constantly under the control of opposed 115 forces tending always to balance each other and hold the valve 31, as it were, in suspension between them; that is to say, the specific apparatus tends constantly to establish a balancing equation between the 120

opposed forces acting upon the valve 31. Such movement of the valve 31 as may occur when that balancing equation is disturbed, takes place practically instantaneously so that a new balancing equation appropriate to the newly initiated conditions is immediately set up.

The actual variation of regulated pressure may result from a number of causes, 10 or a combination of causes, such that the valve 31 may or may not be moved to assist in a re-establishment of the pressure equation above referred to, which holds the valve in balance.

15 Normally, and even at a time when it is desired to maintain constant regulated pressure, some leakage of atmosphere to the chest 12, and various parts communicating therewith, may tend to reduce the degree of exhaust in said chest, whether or not any of the motor pneumatics F are in action. A reduction in regulated exhaust from such cause may be compensated to some extent by leakage between the high exhaust chest 14 20 and the chest 12, as by leakage past the valve 31. If, however, regulated pressure increase enough to disturb a prevailing pressure equation, there may result an upward movement 25 of the valve 31 enlarging the opening between the chests 12 and 14 enough to permit high exhaust to restore the intended regulated exhaust in chest 12. Such action takes place so promptly and quickly, that, in effect, it serves to maintain regulated exhaust substantially constant (until intentionally 30 varied), rather than to restore it.

Each motor pneumatic F, when idle, contains atmosphere which, when the pneumatic is thrown into operation, tends to increase 40 regulated pressure in the chest 12. Obviously, if several motor pneumatics F act simultaneously there may be a considerable increase of regulated pressure. Ordinarily in the operation of the illustrative apparatus, the regulated pressure may be thus subjected to frequent fluctuations by the action of the motor pneumatics. Whenever such fluctuation so increases regulated pressure that a pressure equation is disturbed, 45 the valve 31 may be moved to restore the equation as described. As already suggested, this restoring action takes place so quickly that it is rather a maintaining action in its general effect upon the regulated pressure.

50 From the above it appears that whatever drafts are made upon the regulated pressure chest 12, and from whatever cause, said pressure may be maintained always by the described balancing operation of the forces 55 controlling communication between the chest 12 and 14 by the valve 31. Immediately, however, a deliberate, intentional change is made in the pneumatic conditions in the bellows 34, 35 and 36, or any thereof, the pres-

sure equation is temporarily disturbed, to be restored when a new and different regulated pressure is established.

It will be noted that the regulating action of the described apparatus may serve merely 70 to maintain the desired regulated pressure in spite of any drafts made thereupon, as for instance, by the motor pneumatics. That is to say, the regulation does not necessarily result from varying communication between 75 the high exhaust chest and the regulated pressure chest. For instance, assume that the selection of bellows 34, 35 and 36 containing regulated pressure be so changed that a considerable increase in regulated 80 pressure is demanded to re-establish the pressure equation. Assume further that such change be accompanied by the action of a considerable number of motor pneumatics F, which in effect alone suffices 85 to increase the regulated pressure so as to re-establish the balancing equation. Under such circumstances regulated pressure may be changed from a lower to a higher working level without making necessary any substantial 90 change in the communication between the two chests 12 and 14. Thus in greater or less degree, the mere utilization of regulated pressure in the chest 12, may cooperate 95 with the deliberate variations of pneumatic conditions in the bellows 34, 35 and 36, so that the control of communication between the chests by the valve 31 may be, and frequently it will be, of merely supplemental and auxiliary effect.

100 Normal regulation, in the apparatus disclosed herein as well as in prior art structures, results from the differential between the forces tending to open the regulator valve and the forces tending to close the 105 regulator valve. In the specific apparatus these forces act upon the bellows board 33. It has been assumed that the upwardly acting force represented by the bellows 37, remains uniform while the downwardly acting force represented by the bellows 34, 35 and 36 may be varied to produce incremental changes in playing intensities. In the usual prior art regulator having the capacity for varying playing intensities, the force tending 110 to open the regulator valve has been varied for producing all intensity changes. This force is usually supplied by a spring whose tension is increased by elongation to increase playing intensities and, conversely, 115 whose tension is decreased by contraction to decrease playing intensities. For this purpose the spring is required to be capable of changing its tension as elongated or contracted; and having this capacity, the spring 120 of necessity changes its tension during the normal fluctuating movements of the regulator valve, to which it is connected, when it is only desired to maintain playing intensities uniformly whether one or many notes 125 130

are simultaneously sounded. To a certain degree therefore, during normal regulation by the usual prior art regulator the tension of regulated exhaust must necessarily vary and perfect regulation cannot be obtained. This would result in the uneven playing of a succession of notes which it is desired to sound with uniform intensity.

In an apparatus of the highly refined character herein described which may be used for the automatic reproduction of the manual rendition of a composition by a skilled pianist, such refinements of apparatus are far more essential than in the highly developed instruments of the prior art.

In the apparatus here described incremental changes in playing intensities are obtained in an entirely novel manner by varying the force tending to close the regulator valve (herein, the downwardly acting forces represented by the bellows 34, 35 and 36) and due to this novel construction it is possible to utilize a practically uniform force acting upon and tending to open the regulator valve and still retain in the apparatus the capacity of varying playing intensities by substantially distinct increments. Thus, the imperfections of a regulator which involves the use of a variable force tending to open the regulator valve are entirely eliminated by the use of a uniform force in place thereof.

The manner in which that part of the regulating mechanism operating through bellows 34, 35 and 36 may be governed to initiate different substantially distinct grades of regulated tension will be next described.

Referring again to the drawing, the duct 40 connects the bellows 34 with a valve chamber 49. In said chamber is a duplex valve 50, arranged for opening an upper port to atmosphere and alternatively opening a port from the chamber 49 through a duct 51 to the regulated pressure chest 12. The valve 50 is controlled by a diaphragm of a chamber 54 which communicates with a duct 56. A duplex valve 58 controls a port from the duct 56 to atmosphere, and a second port from the duct 56 to a chamber 59 communicating by a duct 60 with the high exhaust chest 14. The valve 58 is controlled by a diaphragm of a chamber 62 which communicates by a duct 63 with a tracker vent T.

When the tracker vent T is open the diaphragm of chamber 62 and the valve 58 are elevated so as to vent the diaphragm chamber 54 to atmosphere and lift its diaphragm and the valve 50 and vent the duct 40 to atmosphere. The converse of this operation which closes the duct 40 to atmosphere and opens it to regulated tension, will be described hereinafter.

65 The parts just described are triplicated

for controlling the ducts 41 and 42, the corresponding parts of the valve mechanism for the latter being indicated by the numerals, 50, 51, etc., with indices "a" for the valve mechanism for duct 41, and "b" for the valve mechanism for duct 42.

In the valve mechanism for duct 41 it is assumed that the duct 63^a to the tracker vent T^a is open to atmosphere; this lifts the diaphragm of chamber 62^a, venting chamber 54^a to atmosphere and admitting atmosphere to the duct 41, past the valve 50^a and to the bellows 35. Thus, whenever a tracker vent T, T^a or T^b, is open, atmosphere is admitted to the corresponding bellows 34, 35 or 36.

When one of the valves 50, 50^b is once opened by venting the corresponding tracker duct, the valve preferably continues open even though the tracker vent may be immediately closed. In the specific apparatus this results from the fact that once the valve 58^a, for instance, is opened to admit atmosphere to the diaphragm chamber 54^a, said valve 58^a is held in that position by atmosphere admitted past the valve 58^a into a duct 70^a through a bleeder vent 72^a, and a duct 74^a (shown in dotted lines), which latter communicates with the diaphragm chamber 62^a. The chamber 59^a above the diaphragm communicates as described with the high exhaust chest 14. Thus so long as atmosphere is admitted through duct 70^a to duct 74^a the diaphragm of chamber 62^a will remain lifted and atmosphere will continue in the corresponding bellows 35. The parts just described as pertaining to the valve 50^a are triplicated to cooperate with the valves 50 and 50^b.

From the preceding discussion it will appear that small perforations in a music sheet 105 may be employed to open the tracker vents T, T^a and T^b which may be immediately closed if desired. When used with the illustrative apparatus, each such perforation has the effect of introducing atmosphere to a 110 bellows 34, 35 or 36 and even after the tracker vent is closed, atmosphere will continue in the corresponding bellows until purposely exhausted at any desired subsequent time in a manner such as that about to be 115 described.

The specific apparatus shown in the drawings comprises a single valve mechanism, controlled by a single tracker vent, which may cooperate with all or any of the three 120 above described valve mechanisms, to negative the effect of opening one or more of the tracker vents T, T^a and T^b. This single valve mechanism is shown at the right of Figure 1.

A tractor vent R communicates by its duct 80 with a diaphragm chamber 82. The latter controls a duplex valve 84 which in its alternative positions admits atmosphere to a duct 86 or opens communication be- 125

tween said duct 86 and a duct 88 leading to the high exhaust chest 14. An extension of the duct 86 communicates with each of the three diaphragm chambers 90, 90^a and 90^b.

5 Thus, when atmosphere is admitted to the duct 86, past the valve 84, the diaphragms of the chambers 90, 90^a and 90^b are lifted. In describing the effect of this operation, it is convenient to refer to chamber 90^a and associated parts.

As already stated, the valve 58^a is held in the open position shown, by the fact that atmosphere is present in the ducts 70^a and 74^a. When, however, the diaphragm of chamber 90^a is lifted, it lifts a disk valve 92^a and closes communication between duct 70^a and duct 74^a, thereby closing the latter from atmosphere. At the same time the valve 92^a opens communication between the duct 74^a through the bleeder 72^a, with chamber 94^a which is open to high exhaust through the duct 60^a. In this manner the duct 74^a is connected with high exhaust which bleeds the atmosphere from chamber 62^a thereby permitting valve 58^a to drop, shutting off atmosphere from the diaphragm chamber 54^a and throwing the latter into communication with the chamber 59^a and the high exhaust chest 14 through the duct 60^a. When the diaphragm chamber 54^a is thus exhausted by high exhaust, the valve 50^a is permitted to drop shutting off atmosphere from the duct 41 and throwing the latter into communication with the duct 51^a leading to the regulated pressure chest 12. In this manner, by opening the tracker vent R, the duct 41 and its bellows 35 are closed to atmosphere and opened to regulated pressure.

40 The operation just described, so far as concerns the specific illustrative mechanism depends upon bleeding the diaphragm chamber 62^a. If the tracker duct 63^a be open through its vent T^a, at the time the vent R is opened to initiate the bleeding of diaphragm chamber 62^a, atmosphere will enter the chamber 62^a more rapidly than it can be exhausted therefrom by the described bleeding, therefore the effect of opening the vent R is negated, and in such circumstances that valve 58^a will remain open and atmosphere will continue in the corresponding bellows chamber.

Also, if the tracker vent T, for instance, be 55 open simultaneously with the tracker vent R, the latter will inaugurate a tendency to bleed the chamber 62 and keep the valve 58 closed in the position shown, but the simultaneous opening of the tracker vent T will 60 admit atmosphere to the chamber 62 more rapidly than it can be exhausted by bleeding and therefrom the valve 58 will be lifted in spite of the opening of the tracker vent R.

From the above description it will be understood that whether or not the tracker

vent R be open, the opening of any of the vents T, T^a, T^b will have its normal and usual effect to admit atmosphere to the appropriate bellows or bellows 34, 35 and 36. This will be true if any vent T, T^a, T^b, be 70 opened with or without simultaneously opening the tracker vent R.

On the other hand, if the vent T^a be opened and then closed (atmosphere being thereby admitted to the bellows 34) and the vent R be thereafter opened, the previous effect of opening vent T^a will be negated and the bellows 34 opened to regulated pressure.

The effect of opening and closing the various tracker ducts in the specific mechanism may be readily understood by referring to an illustrative form of perforated music sheet diagrammed in Figure 2 in which are shown four lines of perforations at the top 80 for governing the above described expression controlling tracker vents. The music sheet may be assumed to be travelling in the direction of the arrow in Figure 2. The tracker G is shown in dotted lines in Figure 90 2 the vent T^a being open through the perforation 300 in the sheet. All the other vents are closed. The perforations in the sheet for operating the motor pneumatics may be disregarded for brevity.

When the note sheet and tracker are related as shown in Figure 2, the various valve mechanisms occupy exactly the positions shown in Figure 1. If now the music sheet progresses in the direction of the arrow, perforation 301 will presently open the vent R; this will lift the diaphragm of chamber 82; open the duct 86 to atmosphere; admit atmosphere to diaphragm chamber 90^a; lift valve 92^a; and throw the diaphragm chamber 62^a into communication with the high exhaust chest 14, through the duct 74^a, past the bleeder 72^a, through the chamber 94^a and duct 60^a. This permits the valve 58^a to drop and thereby the diaphragm chamber 54^a is exhausted as described, with the final result that the duct 41 and bellows 35 are closed to atmosphere and opened to regulated pressure. In these circumstances regulated pressure is present in all of the bellows 34, 35 115 and 36 and the playing is at the lowest intensity.

When the music sheet progresses further the perforation 302 opens the vent T and, as will be understood, thereby opens the 120 duct 40 and bellows 34 to atmosphere. Thereafter a perforation 303 and a perforation 304 register respectively and simultaneously with the vents R and T^a. The perforation 303 negates the previous effect of the perforation 302 and opens the bellows 34 to regulated pressure. The perforation 303 is ineffective, however, in respect to perforation 304 which opens the vent T^a and thereby admits atmosphere to the bellows 35. 130

As the note sheet progresses further, perforations 305 and 306 open the vents T and T^b which admit atmosphere to the bellows 34 and 35. The previous effect of the perforation 304 endures, and thereby, by reason of the three perforations 304, 305 and 306, atmosphere is present in all of the bellows 34, 35 and 36, and the playing is at highest intensity.

10 Next a perforation 307 opens the vent R and simultaneously a perforation 308 opens the vent T^a. The effect of the perforation 307 is to negative the previous effect of both the perforations 305 and 306 and to open 15 the bellows 34 and 36 to regulated pressure. The perforation 307, however, is ineffective in respect to perforation 308 which merely continues the previously established effect of the perforation 304 leaving the bellows 35 20 still open to atmosphere.

Next perforations 309 and 310 reinstate atmosphere in the bellows 34 and 36 and again all of the bellows 34, 35 and 36 are open to atmosphere.

25 Next a perforation 311 opens the vent R at a time when all the other vents are closed and thereby negatives the effects of all three perforations 308, 309 and 310 with the result that all the bellows 34, 35 and 36 are closed 30 to atmosphere and open to regulated pressure to reduce the playing to lowest intensity.

The preceding description will suffice to indicate the variety of combinations of perforations whereby atmosphere and regulated 35 pressure may be alternated in one or more of the bellows with the resultant variations in regulated pressure and in the intensities of notes played thereby.

40 As will appear to those skilled in the art the usual note perforations may occur in the music sheet or may be related with the described expression-regulating perforations in any practicable manner, as, for instance, 45 by aligning or substantially aligning, the advance end of a note perforation with one or more expression perforations to establish the regulated pressure in the chest 12 for playing the note with desired intensity.

50 The preceding description has been devoted to an illustrative form of apparatus by which substantially distinct grades or degrees of regulated exhaust may be established for playing notes with substantially 55 distinct grades of intensity, each such grade being louder or softer than the next grade by a more or less definite and considerable increment.

Referring again to the regulating capacity 60 of the four bellows 34, 35, 36 and 37—i. e. their joint capacities to maintain uniformity of playing intensity, whether one or many notes be sounded for whatever degree of regulated exhaust may be provided for by 65 the prevailing conditions in the three bel-

lows 34, 35 and 36,—this regulating action has a unique, highly important accuracy, sensitiveness, rapidity and uniformity of action, all of which are extremely desirable in an instrument for reproducing manual 70 renditions. Obviously, an instrument which is intended to produce automatically the minutiae of expression and tone coloring which characterize a manual performance by a skilled artist, should have extreme refinements and accuracy of operation which would be largely or wholly unnecessary in the less highly developed instruments of the prior art which are mainly subject only to manual control.

75 One of the deficiencies in prior art regulators has already been pointed out, i. e., that arising from the fact that the regulating movements of the regulator valve produce changes in the tension of the regulating spring, and thereby render the normal regulation inaccurate. Such deficiencies are practically eliminated, in the present apparatus by reason of the fact that the tension in the bellows 37 is maintained effectually 80 uniform so as to oppose uniformly the pull by the bellows 34, 35 and 36. It might be possible to exert the desired uniform pull in opposition to the bellows 34, 35 and 36 by means of a very long spring, the tension 85 of which would be only negligibly changed by elongations or contractions due to the movements of the bellows board 33, but the compass of the commercial player piano and the like does not readily admit of the use 90 of a spring of sufficient length to insure the described advantages. A preferred embodiment of this invention utilizes, instead of a regulator spring, a pneumatic system about 95 to be described, which exerts a pneumatic pull through the bellows 37 in opposition to the bellows 34, 35 and 36; said pneumatic pull being maintained uniform and being corrected when necessary to counteract any 100 tendency toward variation on account of leakage or movements of the bellows 105 board 33.

Throughout the preceding description of that part of the regulator acting through bellows 34, 35 and 36, and the valve mechanisms associated therewith, it has been assumed that a substantially uniform upward pressure is exerted upon the board 33 by reason of the condition of uniform partial exhaust in bellows 37. This substantially 110 uniform degree of exhaust may be maintained at all times throughout the operation 115 of the instrument regardless of the pneumatic condition within any one of the bellows 34, 35 and 36. For convenience in the 120 following description of that part of the regulator controlling this upward pressure on the board 33 and the consequent upward pull on the regulator valve 31, it may be assumed for the present that the bellows 34, 35 125 130

and 36 constitute a single regulating pneumatic merely for maintaining uniformity of playing intensity whether many or few notes are sounded concurrently. The capacity of the apparatus to produce incremental changes in playing intensities may be disregarded. For example, it may be assumed that regulated exhaust is present in all the bellows 34, 35 and 36, the result being a maximum downward pressure on the board 33 and valve 31.

The bellows 37 is at all times in free communication through a duct 100 with a pneumatic 101 preferably of larger interior volume than the bellows 37. Because the duct 100 at all times provides free communication between the bellows 37 and the pneumatic 101 this bellows, this pneumatic, and the duct 100 form and may be regarded as a single air container having the two movable walls 33 and 349. One end of a spring 102 is fast to the movable board of the pneumatic 101; the other end being attached to an adjustable screw 103 threaded in a stationary block 104. A stop 105 is provided to limit the expanding movement of the pneumatic 101. Further means, presently to be described, are provided for automatically maintaining a uniform degree of exhaust in pneumatic 101, and, due to the open connection with bellows 37, thereby maintaining at all times, except when intentionally varied as hereinafter described, a substantially uniform upward pressure upon the board 33 and exerting a consequent uniform upward pull on the regulator valve. The bellows 37, duct 100, pneumatic 101, spring 102 and the valve mechanism presently to be described, are the specific embodiment herein shown of what may be termed the regulator tension system, that is, the means for tensioning the regulator pneumatic in opposition to the downward pressure on the board 33 due to the presence of regulated exhaust in bellows 34, 35 and 36, or any of them.

The pneumatic 101 may be exhausted through a duct 106 which provides the only means by which air may be admitted to or exhausted from the pneumatic regulator tension system, excepting of course, the leakage of air into said system due to the natural limitations of the usual construction employed. The duct 106 is connected with a valve chamber 107 formed within a valve block 108 preferably mounted adjacent the pneumatic 101. This valve chamber may be provided with a port 109 to atmosphere and a port 110 to an exhaust chamber 111. The latter chamber may be suitably connected with a source of exhaust, preferably high exhaust. A valve 112, mounted in valve chamber 107, controls ports 109 and 110 and is normally operated as hereinafter de-

scribed to control the degree of exhaust in the duct 106, pneumatic 101, duct 100 and bellows 37. This valve is governed by a diaphragm 113 of a diaphragm chamber 114. The degree of exhaust in diaphragm chamber 114 is in turn governed by bleed passages from said chamber to atmosphere and exhaust respectively; the relative capacities of these bleeds being varied to change the pneumatic condition in diaphragm chamber 114 as occasion may require.

Diaphragm chamber 114 may be exhausted through a bleed 115 connecting the exhaust chamber 111 with a duct 116 which opens into the diaphragm chamber. In the specific apparatus the capacity of this bleed passage is constant.

The atmosphere bleed to the diaphragm chamber 114 is through a port 117 and the duct 116. This atmosphere bleed is adjustable in capacity by means of a valve 118 which, when at rest, closes the port 117 but in the operation of the apparatus is usually slightly opened so that the influx of atmosphere somewhat reduces the degree of exhaust in diaphragm chamber 114 below that which would normally be determined by the exhaust bleed 115. The relative capacities of the port 117 to atmosphere and the bleed 115 to exhaust are preferably such that a slight opening of the port 117 will equal the full capacity of the fixed exhaust bleed 115. Obviously as the port 117 is progressively opened the influx of atmosphere will soon predominate the exhaust of air through the bleed 115 and reduce the degree of exhaust in the diaphragm chamber 114. Upon a full opening of the port 117 the influx of atmosphere will be sufficiently rapid to practically overcome the exhaust bleed, whereupon the pressure within the diaphragm chamber 114 will approximate atmospheric pressure and permit the valve under the action of high exhaust in chamber 111, to close port 109. It will therefore be seen that with the described arrangement the greater or less throttling of the port 117 by the valve 118 will govern the behavior of the valve 112 which in turn controls the degree of exhaust in the regulator tension system comprising duct 106, pneumatic 101, duct 100 and bellows 37. The manner in which the valve 118 is operated for these purposes will be presently described. For the present it suffices to say that when there is a tendency to reduce the degree of exhaust in the regulator tension system below the desired minimum, the valve 118 is automatically opened to enlarge the atmosphere bleed through the port 117, thereby reducing the degree of exhaust in diaphragm chamber 114, lifting the valve 112 and causing a slightly increased flow of air along the duct 106 from the pneumatic 101, thus withdrawing a greater or less

amount of air from the regulator tension system and negativig the tendency to reduce the degree of exhaust therein.

The flow of air along the duct 106 is somewhat restricted by means conveniently supplied by an adjustable screw 119. This obstruction somewhat retards the effect upon the regulator tension system of the operation of the valve 112, and this slightly retarded action is intended to compensate the more usual and comparatively slight fluctuations in the pneumatic condition of the regulator tension system. This obstruction has the effect of reducing the effective opening of the duct 106 to the valve chamber 107, relatively to atmosphere port 109 and exhaust port 110 thereby permitting a more delicate and refined action of the valve 112.

It is desirable that the apparatus be capable of more rapidly restoring the intended normal pneumatic condition of the regulator tension system and for this purpose additional means are provided. The desirability of having the two means for restoring the desired pneumatic condition in the regulator tension system, slowly and rapidly respectively, will be hereinafter more fully explained.

The duct 106 contains a second adjustable screw 120 which obstructs the duct less than does the screw 119 and a by-pass around the screw 119 is provided by means of passages 121 and 122. When this by-pass is open, a free passage is formed around the obstruction screw 119 and the screw 120 determines the speed of flow of air through the duct 106, which speed may obviously be greater when the by-pass is open than when it is closed. Thus when it is desired to compensate for an extreme fluctuation in the pneumatic condition of the regulator tension system, the by-pass 121-122 is opened. Normally, that is, except upon the occurrence of the extreme fluctuations referred to, the by-pass duct 121 is closed by a valve 123 mounted upon a diaphragm of a diaphragm chamber 124. This chamber is connected by a duct 125 with a valve chamber 126 having a port 127 to atmosphere and a port 128 to the exhaust chamber 111. The valve chamber 126 contains a valve 129 which controls ports 127 and 128. Normally valve 129 is seated to close exhaust port 128 and open atmosphere port 127, thereby admitting atmosphere to the duct 125 and diaphragm chamber 124. This in turn permits valve 123 to be normally seated to close by-pass duct 121.

An extreme fluctuation in the pneumatic condition of the regulator tension system which is desired to be compensated through the agency of the valve 129, is that which occurs whenever the pneumatic 101 is permitted to expand excessively. When this condition arises the valve 129 is automatically lifted to close the atmosphere port 127 and

thereby exhaust the diaphragm chamber 124, open the by-pass 121-122 and leave a freer passage for the flow of air along the duct 106. At the same time the valve 112 is lifted to enlarge the opening of its exhaust port 110 and thereby cause a more rapid flow of air along duct 106 from the pneumatic 101. During the fast correction of an extreme movement of the pneumatic 101 the flow of air along duct 106 will be governed by the adjustable screw 120. The capacity for adjusting the effective opening of the duct 106 at such times permits of appropriate adjustments to prevent throbbing of the valves 112 and 129, which might occur if the flow of air along duct 106 were too fast. Due to the slight variations in operation of different instruments, the adjustable screw 120 provides a convenient means for adjusting each instrument instead of making the duct 106 of standard size for all instruments.

The valve 129 is governed by a diaphragm 130 of a diaphragm chamber 131 which communicates by a duct 132 with a port 133 adjacent the port 117. The port 133 is controlled by the same valve 118 which controls the port 117 already described. The usual exhaust bleed for the diaphragm chamber 131 is provided by a bleed passage 134 like the bleed passage 115.

The valve 118 herein takes the form of a lever hinged at 135 so as to move in a vertical plane and a spring 136 tends to hold the valve in closed position. When the valve is rocked upwardly on its hinge, it first opens the atmosphere bleed 117 and only thereafter, if moved far enough, effectively opens the port 133. The valve 118 is operated in the manner described by means of an arm 137 projecting from the movable board of 105 the pneumatic 101.

The arrangement of the last described parts is such that the normal expansions of the pneumatic 101 (which are intended to be compensated through the valve 112) open 110 more or less as required, the atmosphere bleed 117; while the extreme expansions of the pneumatic 101 (which are intended to be quickly compensated through the agency of valve 129) not only open the port 117 and thereby lift the valve 112, but also effectively open the port 133 and thereby lift the valve 129.

The above described regulating mechanism operates as follows: When the instrument 120 and the feeder bellows are at rest atmosphere is present throughout the regulator tension system and the pneumatic 101 is expanded by the spring 102 to the maximum and rests against its stop 105, the ports 117 and 133 125 being then open. When, however, upon operation of the feeder bellows, the chamber 111 is exhausted, both of the valves 112 and 129 are raised momentarily to their extreme upper positions so that the pneumatic 101, 130

duct 100 and bellows 37 are rapidly exhausted to inaugurate the operation of the pneumatic regulator tension system, thereby at once rendering the regulator operative. The 5 exhaust of the pneumatic 101 collapses it to a certain extent and thereby permits the closing of the port 133 and at least a partial closing of the port 117. The closing of the port 133 results in the dropping of the valve 10 129 which, as already described, closes the valve 123 to cut off the by-pass 121—122 and thereby cause the valve 112 to assume its regulating office.

The valve 112 in performing its regulating 15 function may be so positioned between the exhaust port and the atmosphere port that, when there are no fluctuations in the volume of the regulator tension system, air drawn from the duct 106 will be merely sufficient to 20 compensate for the normal leakage of atmosphere into the pneumatic regulator tension system. Under normal conditions, there may be a constant flow of air through valve chamber 107; this air being supplied principally 25 through the atmosphere port 109 and merely enough air being drawn from duct 106 to compensate for leakage as above suggested.

The pneumatic 101 is controlled in its movements by the differential between the 30 pull of its spring 102 and the action of the exhaust within the pneumatic. With the described arrangement of valves, these opposed forces tend to hold the pneumatic 101 in balance. For example, the pneumatic tends to 35 collapse to that point at which the atmosphere bleed 117 is maintained at such a capacity that the degree of exhaust in the dia- phragm chamber 114 holds the valve 112 in that position in which the relative exhaust 40 and admission of atmosphere past the valve 112 determines a degree of exhaust within the pneumatic 101 which just balances the pull of the spring 102. Any influence tend- 45 ing to disturb this condition of balance will be promptly compensated so that the ulti- mate effect is to maintain within the regu- 50 lator tension system a uniform degree of ex- haust which as will appear to those skilled in the art, will be determined ultimately by whatever tension may be given to the spring 55 102 by its adjustment. The mechanism which intervenes between said spring and the regulating pneumatics effectually eliminates the objections to the use of a mechani- 60 cal spring and serves to transmit the action of said spring in such a way as to refine the regulation and render it extremely accurate. Furthermore, it is preferred that the interior volume of the pneumatic 101 be somewhat 65 greater than the interior volume of bellows 37 so that the expanding and collapsing movements of the pneumatic 101 (in re- sponse to similar movements of the bellows 37) are much less in extent than those of the bellows 37. With such an arrangement

the minimized movements of the pneumatic 101 produce only slight elongations and contractions of the spring 102 and therefore produce only minimum changes in the ten- sion of the spring.

In the playing of the instrument, the sounding of a heavy chord causes a sudden influx of atmosphere to the regulated pres- 75 sure chest 12, thereby reducing the degree of exhaust in said chest. This reduction in the 80 degree of exhaust is communicated to the bellows 34, 35 and 36 so that their pull upon the board 33 is suddenly relaxed. This per- mits the bellows 37 to collapse somewhat and relax its pull upon the air in the regulator 85 tension system, which, in turn may permit the pneumatic 101 to expand somewhat. If this takes place, the expansion of the pneu- 90 matic 101 will enlarge the opening of the atmosphere bleed 117 and thereby as de- 95 scribed above, cause the valve 112 to enlarge the opening of its exhaust port and thereby exhaust from the pneumatic regulator ten- sion system sufficiently to return the pneu- 100 matic 101 to its normal position wherein it 105 will again restrict the atmosphere bleed 117 so as to maintain the desired uniform de- 110 gree of exhaust within the regulator tension system.

If the influx of atmosphere to the chest 12 95 or any other cause, such as an extreme leak- age of atmosphere, diminish the degree of exhaust in the bellows 34, 35 and 36 suffi- 100 ciently to permit an extreme collapsing of the bellows 37 and a corresponding extreme 105 expansion of the pneumatic 101, then not only the atmosphere bleed port 117 will be opened wider, but also the port 133 will be effectively opened so as to open the by-pass 112—122 and permit the rapid exhaust of 110 the pneumatic 101 which will tend to restore it to its normal position. In other words, no matter what the extent of expansion of the pneumatic 101 may be, it is subject to the 115 constant tendency to be returned to that po- sition wherein it maintains such a relation- ship between the atmosphere bleed port 117 and the suction bleed 115, as to cause the valve 112 to maintain a uniform degree of exhaust within the regulator tension system. 120

In an apparatus embodying features of the invention just disclosed, the operation of the parts may be such that the fluctuations in the conditions of the pneumatic regulator system of perceptible fluctuations which are 125 compensated by perceptible movements of the parts. Generally speaking, however, the compensating operations of the parts take place with sufficient rapidity to produce for all practical purposes the effect of main- taining desired uniform conditions rather than the effect of correcting those conditions when they have fluctuated from the intended normal. In any case, the apparatus has the capacity to cause the pull upon the regu- 130

lator by the so-called regulator tension system, to be substantially uniform.

The regulator tension system above described, in addition to its capacity of maintaining substantial uniformity of tension upon the regulator pneumatic, possesses also the capacity of varying playing intensities by varying the upward pull upon the regulator. It will be readily understood by those skilled in the art, that a crescendo operation, i. e. a continuously progressive increase in playing intensities may be produced by gradually increasing the tension on the regulator opposing the pressure caused by the presence of regulated exhaust within the regulator pneumatic (herein exemplified by bellows 34, 35 and 36). It will be similarly evident that a slow increase in tension will produce a slow crescendo, and that a fast increase in tension will produce a fast crescendo. Conversely, fast and slow diminuendos may be produced by correspondingly decreasing the tension on the regulator. As hereinafter explained the regulator heretofore described may be employed for producing crescendo and diminuendo effects at different speeds, thereby producing still further refinements in the playing of the instrument, while maintaining all of the important refinements in regulation.

As previously described the pneumatic 101 of the regulator tension system tends normally to position itself so as to determine a uniform tension on the spring 102 and a consequent uniform tension on the regulator pneumatics. Through the agency of the valve mechanism operatively connected therewith, the pneumatic 101 tends to restore itself to this position if its original self-adjustment is disturbed by movements of the board 33. It will be apparent that if the pneumatic 101 is collapsed beyond this point of normal self-adjustment, an elongation of the spring 102 will take place. The tension of the spring is thereby increased to govern an accompanying increase in the degree of exhaust within the pneumatic 101. This increase in the degree of exhaust will occur simultaneously in the bellows 37 and cause a corresponding increase in the upward pressure on the board 33 and a consequent increase in the upward pull on the regulator valve. The foregoing will result if the valve 112 is lifted to close atmosphere port 109 and held in lifted position for a substantial length of time. The duct 106 is thereby placed in direct communication with high exhaust in exhaust chamber 111, and the air contained in the regulator tension system is slowly exhausted past the more restricted obstruction screw 119. This will continue as long as the valve 112 is held in raised position, or until the pneumatic 101 is completely collapsed. The collapse of the pneumatic 101 and the increase in tension of the

spring 102 as it is elongated, is accompanied by a corresponding increase in the degree of exhaust in the regulator tension system which will continue until it approximates that of high exhaust. This operation will slowly increase the upward pull on the regulator valve and modify the regulation to produce a slow crescendo.

If the valve 112 be allowed to drop and entirely close the exhaust port 110 during or after a crescendo operation, atmosphere will bleed into duct 106 past the more restricted obstruction screw 119, and from this duct into the pneumatic 101. The pneumatic 101 will gradually expand, under the influence of the spring 102, and as the tension of the spring 102 decreases, the degree of exhaust within pneumatic 101 will similarly decrease. This decrease in the degree of exhaust will occur simultaneously in bellows 37 and thereby decrease the upward pull on the regulator valve to modify the regulation and produce a slow diminuendo.

If valve 129 is raised to admit exhaust to diaphragm chamber 124 and open by-pass valve 123, and valve 112 is raised simultaneously therewith, air will be quickly exhausted from the pneumatic 101 through by-pass 121—122 which affords a freer passage for air along the duct 106. In this case the speed of flow will be controlled by the adjustment of the obstruction screw 120. This results in a fast collapse of the pneumatic 101, and a correspondingly fast increase in the degree of exhaust within the regulator tension system, thereby ultimately producing a fast crescendo.

If valve 129 is held in raised position and valve 112 is allowed to drop during or after a crescendo operation, air will bleed into the pneumatic 101 along the duct 106 and through by-pass 121—122. This will result in a correspondingly fast expansion of the pneumatic 101 with the ultimate effect of a fast diminuendo.

During the production of crescendo and diminuendo effects by means of the described apparatus, the regulating functions of the regulator tension system are still preserved. For instance, during the progress of a crescendo a plurality of notes may be simultaneously sounded by the playing pneumatics, whereupon the regulator will respond with a sudden opening of the valve 31 and the corresponding upward movements of the board 33. This movement momentarily decreases the volume of bellows 37 which will tend to decrease the degree of exhaust within the regulator tension system. Inasmuch as this tendency to decrease the degree of exhaust occurs simultaneously in pneumatic 101 there will be a momentary relaxation of the pull on the spring 102 and a slight contraction of the spring. Due to the relatively small movements of the regulator

valve the volume change in the bellows 37 will not be very great, but however great it may be it will be so absorbed in the larger volume of pneumatic 101 that the movement

5 of its movable board, necessary to compensate the volume decrease of bellows 37, will be much less than the movement of the board 33, thus insuring a relatively small and practically negligible change in tension 10 of the spring 102. Moreover as the playing intensities increase a slight variation in intensity is not as noticeable as the same variation would be when the playing intensities are at or near the minimum.

15 The above described operations of the regulator tension system for producing crescendos and diminuendos may be controlled by any practicable means, manually governed or otherwise, which will serve to

20 govern properly the valves 112 and 129. For illustration the duct 116 having the port 117 may be connected by a duct 138 with a vent in the tracker bar to be opened by perforations in the music sheet to produce slow

25 crescendos and to be closed to permit the ensuing slow diminuendos; and the duct 132 having the port 133 may be connected by a duct 139 to another tracker vent to be opened when the crescendos or diminuendos

30 or either of them are to be made rapidly. Thus by merely connecting the appropriate parts of the regulator tension system to the tracker bar, the pneumatic regulator tension system may be made automatically to serve, 35 in addition to its ordinary regulating functions, in the production of crescendos and diminuendos at different speeds.

For illustrative purposes, tracker ducts 138 and 139 are shown as leading to tracker 40 vents correspondingly numbered. Referring to Figure 2, perforation 315 is adapted to open tracker vent 138 and inaugurate a slow crescendo operation. The crescendo will continue until the playing intensity has

45 been raised to the loudest point to which it may be brought by the increase of exhaust tension within the regulator tension system and if it is desired to maintain the playing intensity at this high level the perforation

50 315 may be continued indefinitely. If, however, it is desired to inaugurate a slow diminuendo operation, the perforation 315 will be terminated at a point where it is desired to begin the diminuendo and a slow

55 diminuendo will then occur. Perforations 317 and 318 are adapted to open tracker vents 138 and 139 simultaneously thus inauguring a fast crescendo. If now a fast diminuendo is desired to be produced the

60 perforation 317 will be terminated and the perforation 318 prolonged sufficiently to hold the valve 129 in raised position until the playing intensity has again resumed the point from which it started as controlled by

65 this portion of the apparatus. If again it

is desired to inaugurate a slow crescendo the perforation 319 may be employed to open tracker vent 138 and if during the progress of the slow crescendo it is desired to superpose a fast crescendo thereon, a perforation 324, having its advance end behind that of perforation 319, may be employed to subsequently open tracker vent 139, whereupon the remainder of the crescendo operation will take place at the greatest speed. 70 As perforation 324 is shown it would cause, after the termination of perforation 319, a fast diminuendo. These combinations of crescendo and diminuendo effects at varying speeds are given merely by way of illustration and those skilled in the art will realize that other effects may be produced by other perforations in the note sheet. 80

The utilization of the bellows 34, 35 and 36, to produce changes in playing intensities by distinct increments or steps, as previously described, and the variation in the pull of the regulator tension system to produce crescendo and diminuendo effects, may be combined to advantage all as will be 85 realized by those skilled in the art. By way of illustration it may be assumed that the pneumatic condition within the bellows 34, 35 and 36 may determine the starting point in a scale of intensities at which crescendo 90 and diminuendo effects are to be produced, thereby these effects may be superposed as it were upon an already existing intensity regulation. 95

Furthermore, the playing intensity may 100 be increased by sudden practically instantaneous steps (utilizing the bellows 34, 35 and 36) which steps may be superposed upon a crescendo which is in progress, thereby for example particularly emphasizing some 105 note or notes in the crescendo, and thereafter permitting previously inaugurated crescendo to continue. Likewise with diminuendo effects. Such effects and many others may be produced by properly combining the crescendo and diminuendo effects with each other and with the increasing and decreasing of intensities by the incremental or step changes. The appropriate perforations to be made in the note 110 sheet will be sufficiently understandable. It is deemed unnecessary to enlarge further upon the description of these various combined effects since they are readily ascertainable by those skilled in the art. 115

It is to be understood that the invention is not limited to the specific details of construction, organization and mode of operation hereinbefore described for purposes of illustration. On the contrary the invention 125 may be variously modified and embodied within the scope of the subjoined claims.

I claim as my invention:

1. An instrument of the character described comprising, in combination, play- 130

- ing pneumatics; a main source of power for operating said playing pneumatics; a valve interposed between the main source of power and said playing pneumatics; a 5 pneumatic operatively connected to and tending to close said valve; and means operatively connected to and tending to open said valve, including two permanently interconnected pneumatics of relatively different 10 size, the smaller pneumatic being operatively connected to said valve, a spring tending to expand the larger pneumatic, means connecting said larger pneumatic to a valve chamber, a regulator valve in said chamber, 15 a diaphragm and diaphragm chamber controlling said regulator valve, bleeds to exhaust and atmosphere respectively from said diaphragm chamber, means adjustably restricting the connection from said larger 20 pneumatic to said regulator valve chamber, a by-pass around said restriction and a valve controlling the same, means between said by-pass and said larger pneumatic for adjustably restricting the connection there- 25 between, a diaphragm chamber governing said by-pass controlling valve, bleeds to atmosphere and exhaust respectively from said diaphragm chamber, a valve controlling said atmosphere bleeds governed by the 30 position of the movable board of said larger pneumatic, a tracker and ducts to control the regulator valve and by-pass valve from the tracker.
2. An instrument of the character de- 35 scribed comprising, in combination, playing pneumatics; a main source of power for operating said playing pneumatics; a valve interposed between the main source of power and said playing pneumatics; a pneumatic 40 operatively connected to and tending to close said valve; and means operatively connected to and tending to open said valve, including two permanently interconnected pneumatics of relatively different size, the smaller pneumatic being operatively connected to said 45 valve, a spring tending to expand the larger pneumatic, means connecting said larger pneumatic to a valve chamber, a regulator valve in said chamber, a diaphragm and 50 diaphragm chamber controlling said regulator valve, bleeds to exhaust and atmosphere respectively from said diaphragm chamber, means adjustably restricting the connection from said larger pneumatic to 55 said regulator valve chamber, a by-pass around said restriction and a valve controlling the same, means between said by-pass and said larger pneumatic for adjustably restricting the connection there- 60 between, a diaphragm chamber governing said by-pass controlling valve, bleeds to atmosphere and exhaust respectively from said diaphragm chamber, and a valve controlling said atmosphere bleeds governed by the position of
- tion of the movable board of said larger 65 pneumatic.
3. An instrument of the character de- 70 scribed comprising, in combination, playing pneumatics; a main source of power for operating said playing pneumatics; a valve interposed between the main source of power and said playing pneumatics; a pneumatic operatively connected to and tending to close 75 said valve; and means operatively connected to and tending to open said valve, including two permanently interconnected pneumatics of relatively different size, the smaller pneumatic being operatively connected to said 80 valve, a spring tending to expand the larger pneumatic, means providing a restricted connection from said larger pneumatic to a valve chamber, a regulator valve in said chamber, a diaphragm and diaphragm chamber controlling said regulator valve, bleeds to exhaust and atmosphere respectively from 85 said diaphragm chamber, a by-pass around said restricted connection and a valve controlling the same, means between said by- 90 pass and said larger pneumatic for restrict- 95 ing the connection therebetween, a dia- phragm chamber governing said by-pass controlling valve, bleeds to atmosphere and exhaust respectively from said diaphragm chamber, a valve controlling said atmosphere bleeds governed by the position of the movable board of said larger pneumatic, a tracker and ducts to control the regulator valve and by-pass valve from the tracker.
4. An instrument of the character de- 100 scribed comprising, in combination, playing pneumatics; a main source of power for operating said playing pneumatics; a valve interposed between the main source of power and said playing pneumatics; a pneumatic 105 operatively connected to and tending to close said valve; and means operatively connected to and tending to open said valve, including two permanently interconnected pneumatics of relatively different size, the 110 smaller pneumatic being operatively connected to said valve, a spring tending to expand the larger pneumatic, means providing a restricted connection from said larger pneumatic to a valve chamber, a regulator valve in 115 said chamber, a diaphragm and diaphragm chamber controlling said regulator valve, bleeds to exhaust and atmosphere respectively from said diaphragm chamber, a by pass around said restricted connection and a valve 120 controlling the same, means between said by-pass and said larger pneumatic for restrict- 125 ing the connection therebetween, a dia- phragm chamber governing said by-pass controlling valve, bleeds to atmosphere and exhaust respectively from said diaphragm chamber, and a valve controlling said atmosphere bleeds governed by the position of

the movable board of said larger pneumatic.

5. An instrument of the character described comprising, in combination, playing pneumatics; a main source of power for operating said playing pneumatics; a valve interposed between the main source of power and said playing pneumatics; a pneumatic operatively connected to and tending to 10 close said valve; and means operatively connected to and tending to open said valve; including two permanently interconnected pneumatics, the first of said interconnected pneumatics being operatively connected to 15 said valve, a spring tending to expand the second pneumatic, means connecting said second pneumatic to a valve chamber, a regulator valve in said chamber, a diaphragm and diaphragm chamber controlling 20 said regulator valve, bleeds to exhaust and atmosphere respectively from said diaphragm chamber, means restricting the connection from said second pneumatic to said regulator valve chamber, a by-pass around 25 said restriction and a valve controlling the same, means between said by-pass and said second pneumatic for restricting the connection therebetween, a diaphragm chamber governing said by-pass controlling valve, 30 bleeds to atmosphere and exhaust respectively from said diaphragm chamber, a valve controlling said atmosphere bleeds governed by the position of the movable board of said second pneumatic, a tracker, and ducts 35 to control the regulator valve and by-pass valve from the tracker.

6. An instrument of the character described comprising, in combination, playing pneumatics; a main source of power for 40 operating said playing pneumatics; a valve interposed between the main source of power and said playing pneumatics; a pneumatic operatively connected to and tending to close said valve; and means operatively connected to and tending to open said valve, including two permanently interconnected pneumatics; the first pneumatic being operatively connected to said valve, a spring tending to expand the second pneumatic, 45 means connecting said second pneumatic to a valve chamber, a regulator valve in said chamber, a diaphragm and diaphragm chamber controlling said regulator valve, bleeds to exhaust and atmosphere respectively from said diaphragm chamber, and a valve controlling said atmosphere bleed governed by the position of the movable board of said larger pneumatic. 50 means connecting said second pneumatic to a valve chamber, a regulator valve in said chamber, a diaphragm and diaphragm chamber controlling said regulator valve, bleeds to exhaust and atmosphere respectively from said diaphragm chamber, means restricting the connection from said second pneumatic to said regulator valve chamber, a by-pass around said restriction and a valve controlling the same, means between said 55 by-pass and said second pneumatic for restricting the connection therebetween, a diaphragm chamber governing said by-pass controlling valve, bleeds to atmosphere and exhaust respectively from said diaphragm

chamber, and a valve controlling said atmosphere bleeds governed by the position of the movable board of said second pneumatic. 65

7. An instrument of the character described comprising, in combination, playing pneumatics; a main source of power for 70 operating said playing pneumatics; a valve interposed between the main source of power and said playing pneumatics; a pneumatic operatively connected to and tending to close said valve; and means operatively 75 connected to and tending to open said valve, including permanently interconnected pneumatics of relatively different size, the smaller pneumatic being operatively connected to said valve, a spring tending to expand the 80 larger pneumatic, means connecting said larger pneumatic to a valve chamber, a regulator valve in said chamber, a diaphragm and diaphragm chamber controlling said regulator valve, bleeds to exhaust and atmosphere respectively from said diaphragm 85 chamber, and a valve controlling said atmosphere bleed governed by the position of the movable board of said larger pneumatic, a tracker, and a duct to control the regulator valve from the tracker.

8. An instrument of the character described comprising, in combination, playing pneumatics; a main source of power for operating said playing pneumatics; a valve interposed between the main source of power and said playing pneumatics; a pneumatic operatively connected to and tending to close said valve; and means operatively connected to and tending to open said valve; including 90 permanently interconnected pneumatics of relatively different size the smaller pneumatic being operatively connected to said valve, a spring tending to expand the larger pneumatic, means connecting said larger 95 pneumatic to a valve chamber, a regulator valve in said chamber, a diaphragm and diaphragm chamber controlling said regulator valve, bleeds to exhaust and atmosphere respectively from said diaphragm chamber, and a valve controlling said atmosphere bleed governed by the position of the movable board of said larger pneumatic. 100

9. An instrument of the character described comprising, in combination, playing 115 pneumatics; a main source of power for operating said playing pneumatics; a valve interposed between the main source of power and said playing pneumatics; a pneumatic operatively connected to and tending to close said valve; and means operatively connected to and tending to open said valve, including two permanently interconnected pneumatics, the first pneumatic being operatively connected to said valve, a spring tending to expand the second pneumatic, means connecting said second pneumatic to a valve chamber, a regulator valve in said chamber, a

diaphragm and diaphragm chamber controlling said regulator valve, bleeds to exhaust and atmosphere respectively from said diaphragm chamber, a valve controlling said atmosphere bleed governed by the position of the movable board of said second pneumatic, a tracker, and ducts to control the regulator valve from the tracker.

10. An instrument of the character described comprising, in combination, playing pneumatics; a main source of power for operating said playing pneumatics; a valve interposed between the main source of power and said playing pneumatics; a pneumatic 70 operatively connected to and tending to close said valve; and means connected to and tending to open said valve, including two permanently interconnected pneumatics of relatively different size, the smaller pneumatic 75 being operatively connected to said valve, a spring tending to expand the larger pneumatic; means governing the degree of exhaust in said interconnected pneumatics, a tracker, and tracker controlled ducts governing said automatic means to vary the degree of exhaust in said interconnected pneumatics at varying speeds.

11. An instrument of the character described comprising, in combination, playing pneumatics; a main source of power for operating said playing pneumatics; a valve interposed between the main source of power and said playing pneumatics; a pneumatic 80 operatively connected to and tending to close said valve; and means connected to and tending to open said valve, including two permanently interconnected pneumatics, the first pneumatic being operatively connected to said valve, a spring tending to expand the second pneumatic, means governing the degree of exhaust in said interconnected pneumatics. 85

12. An instrument of the character described comprising, in combination, playing pneumatics; a main source of power for operating said playing pneumatics; a valve interposed between the main source of power and said playing pneumatics; a pneumatic 90 operatively connected to and tending to close said valve; and means connected to and tending to open said valve, including two permanently interconnected pneumatics of relatively different size, the smaller pneumatic 95 being operatively connected to said valve, a spring tending to expand the larger pneumatic and means governing the degree of exhaust in said interconnected pneumatics.

13. An instrument of the character described comprising, in combination, playing pneumatics; a main source of power for operating said playing pneumatics; a valve interposed between the main source of power and said playing pneumatics; a pneumatic 100 operatively connected to and tending to close said valve; and means connected to and tending to open said valve, including two permanently interconnected pneumatics of relatively different size, the smaller pneumatic 105 being operatively connected to said valve, a spring tending to expand the larger pneumatic, means governing the degree of exhaust in said interconnected pneumatics, a tracker, and tracker controlled ducts governing said automatic means to vary the degree of exhaust in said interconnected pneumatics.

14. An instrument of the character de-

scribed comprising, in combination, playing pneumatics; a main source of power for operating said playing pneumatics; a valve interposed between the main source of power and said playing pneumatics; a pneumatic 110 operatively connected to and tending to close said valve; and means connected to and tending to open said valve, including two permanently interconnected pneumatics of relatively different size, the smaller pneumatic 115 being operatively connected to said valve, a spring tending to expand the larger pneumatic; means governing the degree of exhaust in said interconnected pneumatics, a tracker, and tracker controlled ducts governing said automatic means to vary the degree of exhaust in said interconnected pneumatics at varying speeds.

15. An instrument of the character described comprising, in combination, playing pneumatics; a main source of power for operating said playing pneumatics; a valve interposed between the main source of power and said playing pneumatics; a pneumatic 120 operatively connected to and tending to close said valve; and means connected to and tending to open said valve, including two permanently interconnected pneumatics, the first pneumatic being operatively connected to said valve, a spring tending to expand the second pneumatic, means governing the degree of exhaust in said interconnected pneumatics. 125

16. An instrument of the character described comprising, in combination, playing pneumatics; a main source of power for operating said playing pneumatics; a valve interposed between the main source of power and said playing pneumatics; a pneumatic 130 operatively connected to and tending to close said valve; and means connected to and tending to open said valve, including two permanently interconnected pneumatics, the first pneumatic being operatively connected to said valve, a spring tending to expand the second pneumatic, means automatically governing the degree of exhaust in said interconnected pneumatics, a tracker, and tracker controlled ducts governing said automatic means to vary the degree of exhaust in said interconnected pneumatics. 135

17. An instrument of the character described comprising, in combination, playing pneumatics; a main source of power for operating said playing pneumatics; a valve interposed between the main source of power and said playing pneumatics; a pneumatic 140 operatively connected to and tending to close said valve; and means connected to and tending to open said valve, including two permanently interconnected pneumatics, the first pneumatic being operatively connected to said valve, a spring tending to expand the second pneumatic, means governing the degree of exhaust in said interconnected pneumatics, a tracker, and tracker controlled ducts 145

governing said automatic means to vary the degree of exhaust in said interconnected pneumatics at varying speeds.

17. An instrument of the character described comprising, in combination, playing pneumatics; a main source of power for operating said playing pneumatics; a valve interposed between the main source of power and said playing pneumatics; a pneumatic operatively connected to and tending to close said valve; and means operatively connected to and tending to open said valve, including two permanently interconnected pneumatics of relatively different size, the smaller pneumatic being operatively connected to said valve, a spring tending to expand the larger pneumatic, and means for governing the tension of said spring.

18. An instrument of the character described comprising, in combination, playing pneumatics; a main source of power for operating said playing pneumatics; a valve interposed between the main source of power and said playing pneumatics; a pneumatic operatively connected to and tending to close said valve; and means operatively connected to and tending to open said valve, including two permanently interconnected pneumatics of relatively different size, the smaller pneumatic being operatively connected to said valve, a spring tending to expand the larger pneumatic, and means for governing the tension of said spring, a tracker, and tracker controlled ducts governing said automatic means to vary the tension of said spring.

19. An instrument of the character described comprising, in combination, playing pneumatics; a main source of power for operating said playing pneumatics; a valve interposed between the main source of power and said playing pneumatics; a pneumatic operatively connected to and tending to close said valve; and means operatively connected to and tending to open said valve, including two permanently interconnected pneumatics of relatively different size, the smaller pneumatic being operatively connected to said valve, a spring tending to expand the larger pneumatic, means for governing the tension of said spring, a tracker, and tracker controlled ducts governing said automatic means to vary the tension of said spring at different speeds.

20. An instrument of the character described comprising, in combination, playing pneumatics; a main source of power for operating said playing pneumatics; a valve interposed between the main source of power and said playing pneumatics; a pneumatic operatively connected to and tending to close said valve; and means operatively connected to and tending to open said valve, including two permanently interconnected pneumatics, one pneumatic being operatively connected to said valve, a spring tending to expand the

other pneumatic, and means for governing the tension of said spring.

21. An instrument of the character described comprising, in combination, playing pneumatics; a main source of power for operating said playing pneumatics; a valve interposed between the main source of power and said playing pneumatics; a pneumatic operatively connected to and tending to close said valve; and means operatively connected to and tending to open said valve, including two permanently interconnected pneumatics, one pneumatic being operatively connected to said valve, a spring tending to expand the other pneumatic, means for governing the tension of said spring, a tracker, and tracker controlled ducts governing said automatic means to vary the tension of said spring.

22. An instrument of the character described comprising, in combination, playing pneumatics; a main source of power for operating said playing pneumatics; a valve interposed between the main source of power and said playing pneumatics; a pneumatic operatively connected to and tending to close said valve; and means operatively connected to and tending to open said valve, including two permanently interconnected pneumatics, one pneumatic being operatively connected to said valve, a spring tending to expand the other pneumatic, means for governing the tension of said spring, a tracker, and tracker controlled ducts governing said automatic means to vary the tension of said spring at different speeds.

23. An instrument of the character described comprising, in combination, playing pneumatics; a main source of power for operating said playing pneumatics; a valve interposed between the main source of power and said playing pneumatics; a pneumatic operatively connected to and tending to close said valve; means operatively connected to and tending to open said valve; including an air container having two movable walls, one of said movable walls being operatively connected to said valve; a spring connected to the other said movable wall, means connecting said container to atmosphere and exhaust respectively, a regulator valve in said connection, a diaphragm and diaphragm chamber controlling said regulator valve, bleeds to exhaust and atmosphere respectively from said diaphragm chamber, means restricting the connection from said container to said regulator valve, a by-pass around said restriction and a valve controlling the same, a diaphragm and diaphragm chamber governing said by-pass controlling valve, bleeds to atmosphere and exhaust respectively from said diaphragm chamber, a valve controlling said atmosphere bleeds and governed by the position of the second movable wall, a tracker, and ducts

to control the regulator valve and by-pass valve from the tracker.

24. An instrument of the character described comprising, in combination, playing pneumatics; a main source of power for operating said playing pneumatics; a valve interposed between the main source of power and said playing pneumatics; a pneumatic operatively connected to and tending to close 5 said valve; means operatively connected to and tending to open said valve, including an air container having two movable walls, one of said movable walls being operatively connected to said valve, a spring connected to 10 the other said movable wall, means connecting said container to atmosphere and exhaust respectively, a regulator valve in said connection, a diaphragm and diaphragm chamber controlling said regulator valve, bleeds 15 to atmosphere and exhaust respectively from said diaphragm chamber, means restricting the connection from said container to said regulating valve, a by-pass around said restriction and a valve controlling same, a 20 diaphragm and diaphragm chamber governing said by-pass controlling valve, bleeds to atmosphere and exhaust respectively from said diaphragm chamber, and a valve controlling said atmosphere/bleeds and governed 25 by the position of the second movable wall.

25. An instrument of the character described comprising, in combination, playing pneumatics; a main source of power for 30 operating said playing pneumatics; a valve interposed between the main source of power and said playing pneumatics; a pneumatic operatively connected to and tending to close said valve; means operatively connected to and tending to open said valve including an air container having two movable walls, one of said movable walls being operatively connected to said valve, a spring connected to the other said movable wall, 35 means connecting said container to atmosphere and exhaust respectively, a regulator valve in said connection, a diaphragm and diaphragm chamber controlling said regulator valve, bleeds to exhaust and atmosphere 40 respectively from said diaphragm chamber, a valve controlling said atmosphere bleeds and governed by the position of the second movable wall, a tracker, and ducts to control the regulator valve from the tracker. 45

50 26. An instrument of the character described comprising, in combination, playing pneumatics; a main source of power for operating said playing pneumatics; a valve interposed between the main source of power and said playing pneumatics; a pneumatic 55 operatively connected to and tending to close said valve; means operatively connected to and tending to open said valve including an air container having two movable walls, one of said movable walls being operatively connected to said valve, a spring connected to the other said movable wall, and means to maintain a substantially uniform degree of 60 exhaust in said container.

65 27. An instrument of the character described comprising, in combination, playing pneumatics; a main source of power for operating said playing pneumatics; a valve interposed between the main source of power and said playing pneumatics; a pneumatic operatively connected to and tending to close 70 said valve; means operatively connected to and tending to open said valve including an air container having two movable walls, one of said movable walls being operatively connected to said valve, a spring connected to the other said movable wall, means connecting said container to atmosphere and exhaust respectively, a regulator valve in said connection, and means to automatically actuate 75 said regulator valve from said second movable wall.

28. An instrument of the character described comprising, in combination, playing pneumatics; a main source of power for operating said playing pneumatics; a valve 80 interposed between the main source of power and said playing pneumatics; a pneumatic operatively connected to and tending to close said valve; means operatively connected to and tending to open said valve including an air container having two movable walls, one of said movable walls being operatively connected to said valve, a spring connected to the other said movable wall, means connecting said container to atmosphere and exhaust 85 respectively, a regulator valve in said connection, and means to automatically actuate said regulator valve from said second movable wall.

29. An instrument of the character described comprising, in combination, playing pneumatics; a main source of power for operating said playing pneumatics; a valve interposed between the main source of power and said playing pneumatics; a pneumatic 90 operatively connected to and tending to close said valve; means operatively connected to and tending to open said valve including an air container having two movable walls, one of said movable walls being operatively connected to said valve, a spring connected to the other said movable wall, means connecting said container to atmosphere and exhaust respectively, a regulator valve in said connection, means to automatically actuate said regulator valve from said second movable wall, a tracker, and ducts to control said regulator valve from the tracker. 95

30. An instrument of the character described comprising, in combination, playing 100 pneumatics; a main source of power for operating said playing pneumatics; a valve interposed between the main source of power and said playing pneumatics; a pneumatic operatively connected to and tending to close 105 said valve; means operatively connected to and tending to open said valve including an air container having two movable walls, one of said movable walls being operatively connected to said valve, a spring connected to the other said movable wall, and means to maintain a substantially uniform degree of 110 exhaust in said container.

31. An instrument of the character described comprising, in combination, playing 115 pneumatics; a main source of power for operating said playing pneumatics; a valve interposed between the main source of power and said playing pneumatics; a pneumatic operatively connected to and tending to close 120 said valve; means operatively connected to and tending to open said valve including an air container having two movable walls, one of said movable walls being operatively connected to said valve, a spring connected to the other said movable wall, and means to maintain a substantially uniform degree of 125 exhaust in said container.

pneumatics; a main source of power for operating said playing pneumatics; a valve interposed between the main source of power and said playing pneumatics; a pneumatic 5 operatively connected to and tending to close said valve; means operatively connected to and tending to open said valve, including an air chamber having two movable walls, one of said movable walls being operatively 10 connected to said valve, a spring connected to the other said movable wall, means to maintain a substantially uniform degree of exhaust in said container, a tracker, and tracker controlled ducts acting upon said 15 maintaining means to vary the degree of exhaust in said container.

31. An instrument of the character described comprising, in combination, playing pneumatics; a main source of power for operating said playing pneumatics; a valve interposed between the main source of power and said playing pneumatics; a pneumatic 20 operatively connected to and tending to close said valve; means operatively connected to and tending to open said valve including an air container having two movable walls, one of said movable walls being operatively connected to said valve, a spring connected to the other said movable wall, means to maintain 25 a substantially uniform degree of exhaust in said container, a tracker, and tracker controlled ducts acting upon said maintaining means to vary the degree of exhaust in said container at varying speeds.

32. An instrument of the character described comprising, in combination, playing pneumatics; a main source of power for operating said playing pneumatics; a valve interposed between the main source of power 30 and said playing pneumatics; a pneumatic operatively connected to and tending to close said valve; means operatively connected to and tending to open said valve including an air container having two movable walls of 45 different effective areas, the movable wall of smaller area being operatively connected to said valve, a spring connected to the movable wall of larger area, means connecting said container to atmosphere and exhaust respectively, a regulator valve in said connection, a diaphragm and diaphragm chamber controlling said regulator valve, bleeds to exhaust and atmosphere respectively from said diaphragm chamber, means restricting 50 the connection from said container to said regulator valve; a by-pass around said restriction and a valve controlling the same, a diaphragm and diaphragm chamber governing said by-pass controlling valve, bleeds to atmosphere and exhaust respectively from said diaphragm chamber, a valve controlling said atmosphere bleeds and governed by the position of the 55 larger movable wall, a tracker, and ducts to control the regulator valve from the tracker.

33. An instrument of the character described comprising, in combination, playing pneumatics; a main source of power for operating said playing pneumatics; a valve interposed between the main source of power 60 and said playing pneumatics; a pneumatic operatively connected to and tending to close said valve; means operatively connected to and tending to open said valve, including an air container having two movable walls of 65 different effective areas, the movable wall of smaller area being operatively connected to said valve, a spring connected to the movable wall of larger area, means connecting said container to atmosphere and exhaust respectively, a regulator valve in said connection, a diaphragm and diaphragm chamber controlling said regulator valve, bleeds to exhaust and atmosphere respectively from said diaphragm chamber, a valve controlling said atmosphere bleeds and governed by the position of the larger movable wall, a tracker, and ducts to control the regulator valve from the tracker.

34. An instrument of the character described comprising, in combination, playing pneumatics; a main source of power for operating said playing pneumatics; a valve interposed between the main source of power 70 and said playing pneumatics; a pneumatic operatively connected to and tending to close said valve; means operatively connected to and tending to open said valve, including an air container having two movable walls of different effective areas, the movable wall of smaller area being operatively connected to said valve, a spring connected to the movable wall of larger area, means connecting said container to atmosphere and exhaust respectively, a regulator valve in said connection, a diaphragm and diaphragm chamber controlling said regulator valve, bleeds to exhaust and atmosphere respectively from said diaphragm chamber, means restricting the connection from said container to said regulating valve; a by-pass around said restriction and a valve controlling same, a diaphragm and diaphragm chamber governing said by-pass controlling valve, bleeds to atmosphere and exhaust respectively from said diaphragm chamber, and a valve controlling said atmosphere bleeds and governed by the position of the larger movable wall.

35. An instrument of the character described comprising, in combination, playing pneumatics; a main source of power for operating said playing pneumatics; a valve interposed between the main source of power 85 and said playing pneumatics; a pneumatic operatively connected to and tending to close said valve; means operatively connected to and tending to open said valve; including an air container having two movable walls of different effective areas, the movable wall of smaller area being operatively connected to said valve, a spring connected to the movable wall of larger area, means connecting said container to atmosphere and exhaust respectively, a regulator valve in said connection, a diaphragm and diaphragm chamber controlling said regulator valve, bleeds to exhaust and atmosphere respectively from said diaphragm chamber, a valve controlling said atmosphere bleeds and governed by the position of the larger movable wall, a tracker, and ducts to control the regulator valve from the tracker.

36. An instrument of the character described comprising, in combination, playing pneumatics; a main source of power for operating said playing pneumatics; a valve interposed between the main source of power 100 and said playing pneumatics; a pneumatic operatively connected to and tending to close said valve; means operatively connected to and tending to open said valve, including an air container having two movable walls of 105 different effective areas, the movable wall of smaller area being operatively connected to said valve, a spring connected to the movable wall of larger area, means connecting said container to atmosphere and exhaust respectively, a regulator valve in said connection, a diaphragm and diaphragm chamber controlling said regulator valve, bleeds to exhaust and atmosphere respectively from said diaphragm chamber, a valve controlling said atmosphere bleeds and governed by the position of the larger movable wall, a tracker, and ducts to control the regulator valve from the tracker.

different effective areas, the movable wall of smaller area being operatively connected to said valve, a spring connected to the movable wall of larger area, means connecting 5 said container to atmosphere and exhaust respectively, a regulator valve in said connection, a diaphragm and diaphragm chamber controlling said regulator valve, bleeds to exhaust and atmosphere respectively from 10 said diaphragm chamber, and a valve controlling said atmosphere bleeds and governed by the position of the larger movable area.

36. An instrument of the character described comprising, in combination, playing pneumatics; a main source of power for operating said playing pneumatics; a valve interposed between the main source of power and said playing pneumatics; a pneumatic 15 operatively connected to and tending to close said valve; means operatively connected to and tending to open said valve including an air container having two movable walls of different effective areas, the movable wall 20 of smaller area being operatively connected to said valve, a spring connected to the movable wall of larger area, means connecting said container to atmosphere and exhaust respectively, a regulator valve in said connection, and means to automatically actuate 25 said regulator valve from said larger movable wall.

37. An instrument of the character described comprising, in combination, playing pneumatics; a main source of power for operating said playing pneumatics; a valve interposed between the main source of power and said playing pneumatics; a pneumatic 30 operatively connected to and tending to close said valve; means operatively connected to and tending to open said valve, including an air container having two movable walls of different effective areas, the movable wall of 35 smaller area being operatively connected to said valve, a spring connected to the movable wall of larger area, means connecting said container to atmosphere and exhaust respectively, a regulator valve in said connection, means to automatically actuate said regulator 40 valve from said larger movable wall, a tracker, and ducts to control said regulator valve from the tracker.

38. An instrument of the character described comprising, in combination, playing pneumatics; a main source of power for operating said playing pneumatics; a valve interposed between the main source of power and said playing pneumatics; a pneumatic 45 operatively connected to and tending to close said valve; means operatively connected to and tending to open said valve, including an air container having two movable walls of different effective areas, the movable wall of smaller area being operatively connected 50 to said valve, a spring connected to the mov-

able wall of larger area, and means to maintain a substantially uniform degree of exhaust in said container.

39. An instrument of the character described comprising, in combination, playing pneumatics; a main source of power for operating said playing pneumatics; a valve interposed between the main source of power and said playing pneumatics; a pneumatic 55 operatively connected to and tending to close said valve; means operatively connected to and tending to open said valve, including an air container having two movable walls of different effective areas, the movable wall of smaller area being operatively connected 60 to said valve, a spring connected to the movable wall of larger area, means to maintain a substantially uniform degree of exhaust in said container, a tracker, and tracker controlled ducts acting upon said 65 maintaining means to vary the degree of exhaust in said container.

40. An instrument of the character described comprising, in combination, playing pneumatics; a main source of power for operating said playing pneumatics; a valve interposed between the main source of power and said playing pneumatics; a pneumatic 70 operatively connected to and tending to close said valve; means operatively connected to and tending to open said valve; including an air container having two movable walls of different effective areas, the movable wall of smaller area being operatively connected 75 to said valve, a spring connected to the movable wall of larger area, means to maintain a substantially uniform degree of exhaust in said container, a tracker, and tracker controlled ducts acting upon said 80 maintaining means to vary the degree of exhaust in said container.

41. An instrument of the character described comprising, in combination, playing pneumatics; a main source of power for operating said playing pneumatics; a valve 85 interposed between the main source of power and said playing pneumatics; a pneumatic operatively connected to and tending to close said valve; means operatively connected to 90 and tending to open said valve; including an air container having two movable walls of different effective areas, the movable wall of smaller area being operatively connected to 95 said valve, a spring connected to the movable wall of larger area, means to maintain a substantially uniform degree of exhaust in said container, a tracker, and tracker controlled ducts acting upon said 100 maintaining means to vary the degree of exhaust in said container at different speeds.

41. An instrument of the character described comprising, in combination, playing pneumatics; a main source of power for operating said playing pneumatics; a valve 105 interposed between the main source of power and said playing pneumatics; a pneumatic operatively connected to and tending to close said valve; means operatively connected to and tending to open said valve 110 including an air container having two movable walls, one of said movable walls being operatively connected to said valve, a spring connected to the other said movable wall, and means to vary the pull of said spring 115 upon said second movable wall to vary playing intensities.

42. An instrument of the character described comprising, in combination, playing pneumatics; a main source of power for operating said playing pneumatics; a valve interposed between the main source of power and said playing pneumatics; a pneumatic 120 operatively connected to and tending to close said valve; means operatively connected to 125 and tending to open said valve; including an air container having two movable walls of different effective areas, the movable wall of smaller area being operatively connected 130 to said valve, a spring connected to the mov-

and tending to open said valve including an air container having two movable walls, one of said movable walls being operatively connected to said valve, a spring connected to the other said movable wall, means to vary at different speeds the pull of said spring upon said second movable wall to vary playing intensities at different speeds.

43. An instrument of the character described comprising, in combination, playing pneumatics; a main source of power for operating said playing pneumatics; a valve interposed between the main source of power and said playing pneumatics; a pneumatic operatively connected to and tending to close said valve; means operatively connected to and tending to open said valve including an air container having two movable walls, one of said movable walls being operatively connected to said valve, a spring connected to the other said movable wall, means to vary the pull of said spring upon said second movable wall to vary playing intensities, a tracker, and tracker controlled ducts to govern the variation in the pull of said spring.

44. An instrument of the character described comprising, in combination, playing pneumatics; a main source of power for operating said playing pneumatics; a valve interposed between the main source of power and said playing pneumatics; a pneumatic operatively connected to and tending to close said valve; means operatively connected to and tending to open said valve, including an air container having two movable walls, one of said movable walls being operatively connected to said valve, a spring connected to the other said movable wall, means to vary at different speeds the pull of said spring upon said second movable wall to vary playing intensities, a tracker, and tracker controlled ducts to govern the variation in the pull of said spring upon said second movable wall.

45. An instrument of the character described comprising, in combination, playing pneumatics; a main source of power for operating said playing pneumatics; a valve interposed between the main source of power and said playing pneumatics; a pneumatic operatively connected to and tending to close said valve; means operatively connected to and tending to open said valve including an air container having two movable walls of different effective areas, the movable wall of smaller effective area being operatively connected to said valve, and a spring connected to the movable wall of larger effective area.

46. An instrument of the character described comprising, in combination, playing pneumatics; a main source of power for operating said playing pneumatics; a valve interposed between the main source of power and said playing pneumatics; a pneumatic

operatively connected to and tending to close said valve; means operatively connected to and tending to open said valve including an air container having two movable walls of different effective areas, enclosing a body of air under tension, the movable wall of smaller effective area being operatively connected to said valve, and a spring connected to the movable wall of larger effective area.

47. An instrument of the character described comprising, in combination, playing pneumatics; a main source of power for operating said playing pneumatics, a valve interposed between the main source of power and said playing pneumatics; a pneumatic operatively connected to and tending to close said valve; means operatively connected to and tending to open said valve including an air container having two movable walls, one of said movable walls being operatively connected to said valve, and a spring connected to the other said movable wall.

48. An instrument of the character described comprising, in combination, playing pneumatics; a main source of power for operating said playing pneumatics; a valve interposed between the main source of power and playing pneumatics; a pneumatic operatively connected to and tending to close said valve; means operatively connected to and tending to open said valve, including an air container having two movable walls enclosing a body of air under tension, one of said movable walls being operatively connected to said valve, and a spring connected to the other said movable wall.

49. An instrument of the character described comprising, in combination, playing pneumatics; a main source of power for operating said playing pneumatics; a valve interposed between the main source of power and said playing pneumatics; means operatively connected to and tending to close said valve; and means operatively connected to and tending to open said valve, including two permanently interconnected pneumatics, the first pneumatic being operatively connected to said valve, means tending to expand the second pneumatic, means connecting said second pneumatic to a valve 115 chamber, a regulator valve in said chamber, a diaphragm and diaphragm chamber controlling said regulator valve, bleeds to exhaust and atmosphere respectively from said diaphragm chamber, and a valve controlling said atmosphere bleed governed by the position of the movable board of said second pneumatic.

50. An instrument of the character described comprising, in combination, playing pneumatics; a main source of power for operating said playing pneumatics; a valve interposed between the main source of power and said playing pneumatics; means operatively connected to and tending to close said

valve; and means connected to and tending to open said valve, including two permanently interconnected pneumatics of relatively different size, the smaller pneumatic 5 being operatively connected to said valve, means tending to expand the larger pneumatic and means governing the degree of exhaust in said interconnected pneumatics.

51. An instrument of the character described comprising, in combination, playing pneumatics; a main source of power for operating said playing pneumatics; a valve interposed between the main source of power and said playing pneumatics; means operatively connected to and tending to close said valve; and means connected to and tending to open said valve, including two permanently interconnected pneumatics, the first pneumatic being operatively connected 15 to said valve, means tending to expand the second pneumatic, and means governing the degree of exhaust in said interconnected pneumatics.

52. An instrument of the character described comprising, in combination, playing pneumatics; a main source of power for operating said playing pneumatics; a valve interposed between the main source of power and said playing pneumatics; means operatively connected to and tending to close said valve; and means operatively connected to and tending to open said valve, including two permanently interconnected pneumatics of relatively different size, the smaller pneumatic 35 being operatively connected to said valve, means tending to expand the larger pneumatic, and means for governing the tension of said spring.

53. An instrument of the character described comprising, in combination, playing pneumatics; a main source of power for operating said playing pneumatics; a valve interposed between the main source of power and said playing pneumatics; means operatively connected to and tending to close said valve; and means operatively connected to and tending to open said valve, including two permanently interconnected pneumatics, one pneumatic being operatively connected 45 to said valve, means tending to expand the other pneumatic, and means for governing the tension of said expanding means.

54. An instrument of the character described comprising, in combination, playing pneumatics; a main source of power for operating said playing pneumatics; a valve interposed between the main source of power and said playing pneumatics; means operatively connected to and tending to close said 55 valve; means operatively connected to and tending to open said valve including an air container having two movable walls, one of said movable walls being operatively connected to said valve, means connected to the other said movable wall to press said wall 60 to the 65 other said movable wall to press said wall

outwardly, means connecting said container to atmosphere and exhaust respectively, a regulator valve in said connection, and means to automatically actuate said regulator valve from said second movable wall.

70

55. An instrument of the character described comprising, in combination, playing pneumatics; a main source of power for operating said playing pneumatics; a valve interposed between the main source of power 75 and said playing pneumatics; means operatively connected to and tending to close said valve; means operatively connected to and tending to open said valve; including an air container having two movable walls, one of 80 said movable walls being operatively connected to said valve, means connected to the other said movable wall to press said wall outwardly, and means to maintain a substantially uniform degree of exhaust in said 85 container.

56. An instrument of the character described comprising, in combination, playing pneumatics; a main source of power for operating said playing pneumatics; a valve 90 interposed between the main source of power and said playing pneumatics; means operatively connected to and tending to close said valve; means operatively connected to and tending to open said valve; including an air 95 container having two movable walls of different effective areas, the movable wall of smaller area being operatively connected to said valve, means connected to the movable wall of larger area to press said wall outwardly, and means to maintain a substantially uniform degree of exhaust in said 100 container.

57. An instrument of the character described comprising, in combination, playing 105 pneumatics; a main source of power for operating said playing pneumatics; a valve interposed between the main source of power and said playing pneumatics; means operatively connected to and tending to close said 110 valve; means operatively connected to and tending to open said valve including an air container having two movable walls, one of said movable walls being operatively connected to said valve, means connected to the other said movable wall to press said wall 115 outwardly, and means to vary the action of said last means upon said second movable wall to vary playing intensities.

58. An instrument of the character described comprising, in combination, playing pneumatics; a main source of power for operating said playing pneumatics; a valve interposed between the main source of power 120 and said playing pneumatics; means operatively connected to and tending to close said valve; means operatively connected to and tending to open said valve including an air 125 container having two movable walls of different effective areas, the movable wall of 130

- smaller effective area being operatively connected to said valve, and means connected to the movable wall of larger effective area to press said wall outwardly.

5 59. An instrument of the character described comprising, in combination, playing pneumatics; a main source of power for operating said playing pneumatics; a valve interposed between the main source of power and said playing pneumatics; means operatively connected to and tending to close said valve; means operatively connected to and tending to open said valve including an air container having two movable walls of different effective areas, enclosing a body of air under tension, the movable wall of smaller effective area being operatively connected to said valve, and means connected to the movable wall of larger effective area to press said wall outwardly.

10 60. An instrument of the character described comprising, in combination, playing pneumatics; a main source of power for operating said playing pneumatics, a valve interposed between the main source of power and said playing pneumatics; means operatively connected to and tending to close said valve; means operatively connected to and tending to open said valve including an air container having two movable walls, one of said movable walls being operatively connected to said valve, and means connected to the other said movable wall to press said wall outwardly.

15 61. An instrument of the character described comprising, in combination, playing pneumatics; a main source of power for operating said playing pneumatics; a valve interposed between the main source of power and said playing pneumatics; means operatively connected to and tending to close said valve, an air container having two movable walls one of which is connected to said valve and acts to open said valve, and means whereby the second movable wall acts to maintain constant the pressure in said container to thus maintain constant the regulated pressure.

20 62. An instrument of the character described comprising, in combination, playing pneumatics; a main source of power for operating said playing pneumatics; a regulating valve interposed between said main source of power and said playing pneumatics; means operatively connected to and tending to close said valve; and means connected to the other said movable wall to press said wall outwardly.

25 63. An instrument of the character described comprising, in combination, playing pneumatics; a main source of power for operating said playing pneumatics; a valve interposed between the main source of power and said playing pneumatics; means operatively connected to and tending to open said valve, including an air container having two movable walls one of which is connected to said valve and acts to open said valve, and means whereby the second movable wall acts to maintain constant the pressure in said container to thus maintain constant the regulated pressure, and means for altering the pressure in said container to thus alter the intensity of said regulated pressure.

30 64. An instrument of the character described comprising, in combination, playing pneumatics; a main source of power for operating said playing pneumatics; a regulating valve interposed between said main source of power and said playing pneumatics; means operatively connected to and tending to close said valve; and means operatively connected to and tending to open said valve comprising an air container having two movable walls one of which is connected to said valve, means whereby the second movable wall acts to maintain constant pressure within said container, and means for altering said pressure.

35 65. An instrument of the character described comprising, in combination, playing pneumatics; a main source of power for operating said playing pneumatics; a valve interposed between the main source of power and said playing pneumatics; means operatively connected to and tending to close said valve, an air container having two movable walls one of which is connected to said valve and acts to open said valve, and means whereby the second movable wall acts to maintain constant the pressure in said container to thus maintain constant the regulated pressure.

40 66. An instrument of the character described comprising, in combination, playing pneumatics; a main source of power for operating said playing pneumatics; a regulating valve interposed between said main source of power and said playing pneumatics; and means acting on said valve to regulate the air pressure on the playing pneumatic side of said valve comprising means tending to close said valve, an air container having two movable walls one of which is connected to said valve and acts to open said valve, and means whereby the second movable wall acts to maintain constant the pressure in said container to thus maintain constant the regulated pressure, and means for altering the pressure in said container to thus alter the intensity of said regulated pressure.

45 67. An instrument of the character described comprising, in combination, playing pneumatics; a main source of power for operating said playing pneumatics; a valve interposed between the main source of power and said playing pneumatics; means operatively connected to and tending to close said valve; and means connected to the other said movable wall to press said wall outwardly.

50 68. An instrument of the character described comprising, in combination, playing pneumatics; a main source of power for operating said playing pneumatics; a regulating valve interposed between said main source of power and said playing pneumatics; means operatively connected to and tending to open said valve comprising an air container having two movable walls one of which is connected to said valve, means whereby the second movable wall acts to maintain constant pressure within said container, and means for altering said pressure.

55 69. An instrument of the character described comprising, in combination, playing pneumatics; a main source of power for operating said playing pneumatics; a valve interposed between the main source of power and said playing pneumatics; means operatively connected to and tending to close said valve, an air container having two movable walls one of which is connected to said valve and acts to open said valve, and means whereby the second movable wall acts to maintain constant the pressure in said container to thus maintain constant the regulated pressure, and means for altering the pressure in said container to thus alter the intensity of said regulated pressure.

pneumatics; a main source of power for operating said playing pneumatics; a regulating valve interposed between said main source of power and said playing pneumatics; and means acting on said valve to regulate the air pressure on the playing pneumatic side of said valve comprising means tending to close said valve, an air container having two movable walls one of which is connected to said valve and acts to open said valve, means whereby the second movable wall acts to maintain constant the pressure in said container to thus maintain constant the regulated pressure, and means for continuously altering the pressure in said container to thus alter the regulated pressure to produce a crescendo or diminuendo effect in the playing.

68. An instrument of the character described comprising, in combination, playing pneumatics; a main source of power for operating said playing pneumatics; a valve interposed between the main source of power and said playing pneumatics; a pneumatic operatively connected to and tending to move said valve in one direction; means operatively connected to and tending to move said valve in an opposite direction including an air container having two movable walls of different effective areas, the movable wall of smaller area being operatively connected to said valve, a spring connected to the movable wall of larger area, and means to maintain a substantially uniform degree of exhaust in said container.

69. An instrument of the character described comprising, in combination, playing pneumatics; a main source of power for operating said playing pneumatics; a valve interposed between the main source of power and said playing pneumatics; means operatively connected to and tending to move said valve in one direction; and means connected to and tending to move said valve

in an opposite direction, including two permanently interconnected pneumatics of relatively different size, the smaller pneumatic being operatively connected to said valve, means tending to expand the larger pneumatic and means governing the degree of exhaust in said interconnected pneumatics.

70. An instrument of the character described comprising, in combination, playing pneumatics; a main source of power for operating said playing pneumatics; a valve interposed between the main source of power and said playing pneumatics; means operatively connected to and tending to move said valve in one direction; and means connected to and tending to move said valve in an opposite direction, including two permanently interconnected pneumatics, the first pneumatic being operatively connected to said valve, means tending to expand the second pneumatic, and means governing the degree of exhaust in said interconnected pneumatics.

71. An instrument of the character described comprising, in combination, playing pneumatics; a main source of power for operating said playing pneumatics, a valve interposed between the main source of power and said playing pneumatics; means operatively connected to and tending to move said valve in one direction; and means connected to and tending to move said valve in an opposite direction, including an air container having two movable walls, one of said movable walls being operatively connected to said valve, and means connected to the other said movable wall to press said wall outwardly.

In testimony whereof, I have signed my name to this specification this twenty-fourth day of January, 1917.

CHARLES F. STODDARD.

Certificate of Correction.

It is hereby certified that in Letters Patent No. 1,409,492, granted March 14, 1922, upon the application of Charles F. Stoddard, of New York, N. Y., for an improvement in "Automatic Musical Instruments," an error appears in the printed specification requiring correction as follows: Page 17, line 8, claim 30, for the word "chamber" read *container*; and that the said Letters Patent should be read with this correction therein that the same may conform to the record of the case in the Patent Office.

Signed and sealed this 13th day of June, A. D., 1922.

[SEAL.]

KARL FENNING,

Acting Commissioner of Patents.
